(57) **CLAIM**

The ornamental design for a battery as shown and described.

DESCRIPTION

FIG. 1 is a first perspective view of a battery showing the new design;

FIG. 2 is a second perspective view thereof;

FIG. 3 is a third perspective view thereof;

FIG. 4 is a fourth perspective view thereof;

FIG. 5 is a front view thereof;

FIG. 6 is a back view thereof;

FIG. 7 is a left side elevational view thereof;

FIG. 8 is a right side elevational view thereof;

FIG. 9 is a top view thereof; and,

FIG. 10 is a bottom view thereof.

The broken lines shown in the figures are for the purpose of illustrating portions of the battery and form no part of the claimed design.

1 Claim, 10 Drawing Sheets
